UNITED STATES PATENT OFFICE.

PERRY OLMS TED, OF LOS ANGELES, CALIFORNIA.

PROTRACTOR.

1,247,866.

Specification of Letters Patent. Patented Nov. 27, 1917.

Application filed August 2, 1916. Serial No. 112,688.

To all whom it may concern:

Be it known that I, PERRY OLMS TED, a citizen of the United States, residing at Los Angeles, in the county of Los Angeles and State of California, have invented a new and useful Protractor, of which the following is a specification.

The principal objects of this invention are to provide a protractor of exceedingly simple and convenient construction constituting not only a protractor, but also a tri-square, bevel square, center square, angle finder, and also a simple means whereby without the use of mathematics of any kind, or even tables, the length of the side of any regular polygon to be inscribed in a circle can be determined; to provide a construction by which an angle of any size can be bisected in a very simple manner; in which the angle between the movable straight edge and the stationary straight edge of the protractor can be brought to a sharp point at all small angles; in which a micrometer arrangement is provided whereby settings down to degrees and less, if desired, can be made without the necessity of division lines so close together as to require the use of a glass; in which means can be provided whereby the movable straight edge can be set conveniently to certain specified angles, as for example, ninety and forty-five degrees without the necessity of observing the scales so that this can be done where the light is insufficient and yet provide a device which can be folded up into a small compass. The invention also involves other features including the provision of a scale in combination with the usual degree scale which will show the number of inches rise per foot at any desired angle, and which can be made to show the various angles necessary in building constructions, as for example, the heel cut, plumb cut, and side cut of rafters for a hip roof at various angles.

Reference is to be had to the accompanying drawings in which—

Figure 1 is a front elevation of a preferred embodiment of the invention showing how an angle is bisected by it;

Fig. 2 is an end view showing certain details;

Fig. 3 is a view of the rear side of the protractor showing how it is used for finding various angles necessary in constructing roofs and the like;

Fig. 4 is a front view showing the use of

the device in finding a rise in inches per foot;

Fig. 5 is a similar view showing the setting of the two movable straight edges at ninety and forty-five degrees respectively, and showing some modifications.

Fig. 6 is a view similar to Fig. 1, showing a modified form, and showing the application of the instrument to the problem of inscribing a polygon in a circle, and

Fig. 7 is a similar view showing another modification.

Referring first to the first sheet of drawings, it will be seen that the invention is shown in a form in which the instrument comprises a plate or beam *a* having a pivot *b*, and provided with a straight edge *c* extending from said pivot in one direction. This beam is also provided with a parallel straight edge *d* offset from the straight edge *c* and extending as far as the pivot from the opposite end of the plate. It will be seen that on this beam is a protractor comprising a semi-circular angle scale *e* and in the form shown on this sheet this scale is divided up into divisions of ten degrees each. Also inside this outer scale *e* is a semi-circular scale *f*, the degrees on which are not numbered, but which is divided in a similar manner except that the points of division are half-way between the points of division on the outer semi-circular scale, and from each one of them two lines *g* are drawn one to each of the two adjacent points marked on the scale *e*. These lines *g* are of importance as will appear. The protractor is shown as having its diameter laid off on a straight line of which the straight edge *c* is a part.

Furthermore this side of the device is shown as provided with another scale which, in the form shown, consists of three parts, one *h* parallel with the straight edge *c*, and the other two *j* perpendicular to it. These scales are divided up into equal divisions and the three scales taken together extend entirely around the semi-circle. The purpose of this will be described hereinafter.

Frictionally pivoted at the central point *b* are two arms *k* and *l*. One is shown as on the back and the other on the front. They are provided with semi-circular offset portions covered by the fastening nut and washer *m*, but their inner straight edges are exactly in alignment with the center of this pivot on which they are adapted to swing. It will be noticed that the two straight

edges *c* and *d* are at a distance apart equal to the width of these two arms *k* and *l* so that when they are folded together and brought into contact with the edge *c* the whole instrument is of rectangular form, and all the parts come within the rectangle.

Referring now to the pivoted arm *k* which is on the front, it will be seen that its inner straight edge is scaled in inches and twelfths and that it extends beyond its pivotal point and is provided with four division marks *n* at equal distances apart. These divide up the space between the two graduated circles *e* and *f* into five equal divisions. In this form the line along which these marks are located is radial, that is in exact alinement with the center *b*. The object is to provide a micrometer arrangement whereby the protractor can be divided into a finer degree of division than that indicated by the division points thereon. This will explain why the lines *g* are not radial, but have a certain slant.

In the use of the instrument for this purpose the pivoted arm *k* can be brought for example to the point indicating seventy degrees with its straight edge on that division of the outer circle, and then its angle with the straight edge *c* will be just seventy degrees, but if it is desired to mark off seventy-two degrees it is moved over further until the second of the division marks *n*, on its short arm, registers with the line *g* extending from the seventy degree point of the outer circle to the next point on the inner circle. In this way a fine division can be secured without necessitating the use of finer graduated marks on the outer circle. These divisions on the short arm of the member *k* are much farther apart than the corresponding divisions would have to be on the circle *e*. In the size shown, angles involving divisions under thirty minutes can be readily estimated, and this is finer than is usually necessary in carpenter work. To facilitate the use of this part of the device the space between the circles *e* and *f* is divided by five concentric circles spaced equally.

The use of the scales *h* is also very practical for they are divided up into equal divisions to indicate rises in inches per foot. The first division on the right indicates that if the straight edge *k* is set to correspond with that division it gives a rise of one inch per foot, and so on throughout the scale. The divisions on the two vertical scales are exactly equal to each other. The divisions on the scale *j* shown in these figures constitute a continuation of the two scales *h*.

In the use of this device for bisecting angles, the two arms *k* and *l* have to be employed and for the purpose of using them without reference to the back of the instrument one of them, as for example *k*, can be set to the angle desired, as for example

thirty degrees, and then the rear one *l* brought into register with it, then the front one *k* can be moved to the fifteen degree angle which will bisect the angle formed by the arm *l*, the short arm of the member *k* being used for measuring the angles in both cases.

Where it is desired to find the facts about a polygon to be inscribed in a circle, the instrument is used as shown in Fig. 6. First, the central angle subtended by one side of the polygon is obtained. For example, if it is an octagon, this angle is forty-five degrees. The arm *k* is set at an angle of forty-five degrees from the straight edge *c*. Now the length of the radius of the circle in which it is to be inscribed is laid off on the straight edge *c*, measuring from the center *b*, and also on the adjacent straight edge of the member *k* from the same point. The instrument is so placed, as indicated in Fig. 5, that these two points on the straight edges *c* and *k* will be located on the surface of the circle, and then these points marked in any desired way. This gives the ends of one side of the polygon and the remainder of the figure can be found in any desired way. The geometrical figure appearing on Fig. 6 proves without any mathematical demonstration that this process is correct.

Another feature of the instrument shown in Figs. 1 and 2 is a bar *o* adapted to fit either on the straight edge *c* or on one of the arms *k* or *l*. It has a groove *o'* adapting it to fit frictionally. Its use is to permit the completion of a sharp angle, as indicated in Fig. 1. Without it the apex of the angle would be filled by the washer.

On the rear of the beam are placed scales formed to provide for showing various angles, as may be desired. For example, on the first scale *p* at the top are two sets of lines indicating the plumb cut and end cut respectively of the rafters of a hip roof. For example, if the hip roof has a pitch of seventeen inches to the foot the angles at which the plumb cut and end cut are to be made are indicated by the lines marked 17 on this scale. Various other things can be shown at this place, as for example, the butt cut and miter cut of chords used in constructing polygons or portions of polygons, as for example, in the making of a bay-window. In this case the second scale *q* is shown as marked in this way. The indication 5^s on the scale indicates that a five-sided figure will be made by cutting the timbers so as to have the butt cut or the miter cut represented at different points on that scale. Corresponding cuts for other polygons are also indicated on this scale. It will be understood that various other things may be indicated in a similar way, one or both of the arms *k* and *l* usually being employed to assist the operator in get-

ting the proper angles to mark off on his work.

Another way in which the instrument can be used is in sighting along the straight edge 5 of a pivoted arm *k* or *l* to get an angle, especially an angle of elevation. For this purpose the beam is placed in horizontal position, a level being used, and the arm to be sighted along is tipped to the proper 10 angle and the sight taken along it to the point indicated, as for example, the top of a building or the like. Then the angle indicated without change in the position of any of the parts is read directly on the protractor. 15

The instrument can be used in other ways for various measuring purposes.

For the purpose of setting the arms at the most common angles, as for example, ninety 20 and forty-five degrees, each one is provided with a projection having a straight edge, as for example, *k'* and *l'* at ninety degrees and forty-five degrees respectively to the straight edge. Then as shown in Fig. 5, 25 the operator can readily bring this edge into registration with the straight edge *c* by his fingers without looking at them. Therefore the arms can be set in the dark if desired. This figure also shows some modifications 30 in markings. The lines *g* are replaced by lines *g'* all slanting in the same way instead of alternating. The scale *h* in this case is provided with divisions equal to the divisions on the scales *j*. As half of it is just 35 equal in length to a scale *j*, complementary angles can be found by placing one arm to read on one scale and the other at the correspondingly numbered division on the other. This brings them just ninety degrees apart. 40 The scales *j* shown in Figs. 1 and 5 can of course be put on the same beam.

Fig. 6 has been referred to for the purpose of showing one use of the instrument, but this figure shows a modification in that 45 the arm *k'*, instead of being provided with a straight edge on its short arm in alinement with the pivot, is provided with an edge *h²* at an angle thereto and in this case the lines *g²* which correspond with the lines 50 *g* of the first figure are radial. In this case the reading of the angle is done in the same way as before and the result is equivalent. In this form the four semi-circles between the circles *e* and *f* are omitted as they can 55 be if desired in any of the forms.

Fig. 7 shows another modification in which the straight edge *h³* is located in an angular position in a different way, but also equivalent to the other forms. 60 It will be seen that all these features of utility are secured by an instrument which has only three or four elements and which is practically as simple as any form of tri-square or protractor that has any moving 65 parts at all. This is an important advan-

tage of the device because when not in use it can be folded up into a very compact form, both arms *k* and *l* registering with each other and occupying the space just beyond the straight edge *c*. In this way it 70 can be carried around in the pocket as it has no projecting parts. It is no more trouble than an ordinary two-foot rule.

Although I have illustrated and described only a few forms of the invention I am 75 aware of the fact that other modifications can be made therein by any person skilled in the art without departing from the scope of the invention as expressed in the claims. Therefore I do not wish to be limited to any 80 of the forms shown, but what I do claim is—

1. As an article of manufacture, a measuring device comprising a beam having an angle scale thereon, and an arm having a straight edge pivoted at the center of said 85 scale, the beam having a straight edge and a plurality of scales thereon having identically marked divisions indicating the pitches of hip roofs, and showing the positions at which the arm should be set to 90 give, between it and said straight edge on the beam, the angles of the several cuts for the rafters of the hip roof.

2. As an article of manufacture, a plate having a semi-circular protractor scale, an arm pivoted at the center of said scale and having at each end a scale perpendicular to a diameter of the protractor scale and divided into equal divisions each indicating a rise of an inch per foot, and a third scale 95 100 connecting the other two and so located that the three inclose the protractor scale, and also indicating rises in inches per foot, said third scale constituting a continuation of the end scales.

3. An article of the class described, having a circular angle scale thereon and a straight edge in alinement with its center provided with a scale extending from said center, and an arm having a straight edge 110 pivoted so that the latter straight edge is in alinement with said center, said arm having a projection beyond the center also provided with an edge in alinement with the straight edge of the arm, said angle scale being provided with an inner circle divided up into divisions equal in angular length to the divisions on the outer circle and connected with them by lines, the projection from said arm having an edge thereon equal to the distance 115 120 between said circles radially and having equal divisions thereon, the last named edge and the lines between said circles being located at an angle to each other in all positions of the arm, whereby said arm always intersects one or more of said lines, and whereby the point of intersection indicates the fraction of the angular distance of the arm from the adjacent division on the outer circle.

125 130

4. An article of the class described provided with a pivot, a scale arranged about said pivot as a center and having an outer curve and an inner curve, the outer curve being divided into equal divisions representing multiples of one degree, and the inner curve being divided into divisions each representing the same number of degrees as the ones on the outer curve, straight radial lines connecting the divisions on the inner curve with the adjacent divisions on the outer curve, and an arm pivoted to the main member at said center and having a non-radial edge provided with a scale thereon equal to the distance between said two curves and divided into a number of equal divisions whereby it can be read on said connecting lines to indicate fractions of the divisions on the outer curve.
- 10 5. An article of the class described, comprising a main member or beam and two arms pivoted thereto on the same axis, said member having a protractor on one side, and one of said arms having an extension beyond the pivot adapted to pass over said protractor as the arm swings to indicate the angle that arm makes with respect to the base of the protractor, said beam having a

straight edge in line with said base, the other arm also being set by bringing it into registration with the arm having the extension.

6. An article of the class described, comprising a main member or beam and two arms pivoted thereto on the same axis but on opposite sides, said member having a protractor on one side, and the arm on that side having an extension beyond the pivot adapted to pass over said protractor as the arm swings, whereby an angle can be bisected conveniently by setting the front arm twice, first to the angle itself, and second to half the angle and at the time of the first setting bringing the rear arm into registration with it and keeping it there.

7. An article of the class described, having a main member and an arm pivoted thereto, each having a straight edge, and a member having a groove in one edge adapted to fit on one straight edge, the opposite edge of said member being parallel with the groove, whereby said member is adapted to make a complete sharp angle with the other straight edge.

In testimony whereof I have hereunto affixed my signature.

PERRY OLMSTED.
